SPRINKLER HEAD SHUTOFF TOOL

John Arthur Nelsen, Glendale, and Harry G. Finlay, Burbank, Calif.

Application August 9, 1944, Serial No. 548,744

2 Claims. (Cl. 169—1)

1

This invention relates to shut-off tools for sprinkler heads of automatic fire extinguishing systems.

When a sprinkler head is rendered operative by heat acting upon the fusible link associated with the usual levers of the valve assembly normally closing the head, or is set off by accident, such as by breaking the yoke supporting the adjusting screw or abutment against which one of the levers of the valve assembly normally abuts, it is the usual practice to actuate the shut-off valve by means located remote from the sprinkler head, when the fire is under control or there is no fire, shutting off the supply of water. This often takes considerable time and frequently results in damage to the building and its fixture, and movables in the building. Even after the shut-off valve is closed the "open" head may emit water by gravity flow, for some time so that fire extinguishing systems are provided with drain valves to rid the system of water. Some time may elapse before the water level is below the "open" head even after the drain valve has been opened. Thus the water flow continues from the head for a considerable period of time, during which it is no longer required for fire extinguishing purposes, or after the head has been accidentally broken.

The principal object of this invention is to provide shut-off tools which may be used to quickly and effectively shut off the liquid flow at any sprinkler head of the system, no matter whether such flow is the result of fusing of a link or a broken yoke.

Another object is to provide shut-off tools which may be adjusted for operation with different makes and models of sprinkler heads. The distances between the valve seats and the adjusting screws or abutments in axial alignment with the seats, in different makes and models of sprinkler heads, may vary considerably. The shut-off tools of the present invention may each be initially adjusted for use with the particular sprinkler heads of the system it is to serve and require no further adjustment at the time of actual use if all of the sprinkler heads have substantially the same spacing of valve seats and cooperating abutments, as is usually the case.

A further object of the invention is to provide shut-off tools having valves which may be quickly replaced if worn or damaged without the necessity of dismembering the tools.

Other objects and advantages of the invention will appear in the following detailed description of the preferred embodiment of the invention,

2

taken in connection with the accompanying drawings, forming a part of this specification, and in which drawings:

Fig. 1 is a perspective view of the shut-off tool or equipment for use in stopping the flow of liquid, if the sprinkler head is unbroken, under which circumstance only the primary unit shown to the left engages the sprinkler head, and the other or secondary unit, because of the chain connection, can be used as a weight to assist in shutting off the liquid flow; or, in the event the sprinkler head is broken, shutting off the liquid by both units engaging the sprinkler head.

Fig. 2 is a view in vertical section of the primary unit.

Fig. 3 is a fragmentary view partly in elevation and partly in vertical section of the secondary unit.

Fig. 4 is a side elevation of a sprinkler head and the primary unit in use applied thereto.

Fig. 5 is a front elevation of the parts shown in Fig. 4.

Fig. 6 is a rear elevation of the parts shown in Figs 4 and 5, and with a wire guard applied to the sprinkler head to show the manner in which the primary unit may be used without removing the guard.

Fig. 7 is a view in elevation, showing the primary and secondary units in use applied to a broken sprinkler head.

In the drawings there is shown a suitable or well known form of sprinkler head 8 and in Fig. 6, a guard 9 is shown which in practice may be installed particularly where the head is located in a position otherwise subjecting it to the hazards incident to traffic. However, in most installations the sprinkler head is left unguarded, because of the added cost and labor required to install. It is understood by those skilled in the art that normally these sprinkler heads each has associated with it a pair of coacting levers, a fusible link and a valve, not shown in the drawings and that the sprinkler head is set off by the melting of the fusible link, or by the breaking of the head portion supporting such assembly.

The shut-off tool generally comprises a primary unit 10, a secondary unit 11 and, preferably, a flexible unit 12 connecting the units 10 and 11, so that they may be conveniently carried to and from the place of emergency, are not likely to become misplaced one with respect to the other, and so that the secondary unit may hang pendently from the primary unit when the latter is used with an unbroken sprinkler head, thus serving as a signal, easily observed, that an emer-

gency device is in use and, by its weight, assisting in holding the emergency valve closed.

Briefly the sprinkler head comprises a main body portion 13 provided with a screw threaded nipple 14, for connection with the piping for the extinguishing liquid, port 15 thru the nipple and surrounded by a valve seat 16 and an enlargement 17 providing wrench receiving faces 18, and a shoulder 19; a hubbed yoke 20, the arms 21 of which extend from opposite sides of the enlargement 17 and the hub 22 of which is axially aligned with the port 15 and spaced a suitable distance from the valve seat 16; an abutment 23, usually in the form of a screw carried by the hub 22 so as to also be spaced from the seat 16 and axially aligned with the port 15; and a spreader or distributor 24, secured to the hub in any suitable manner. The distance between the abutment 23 and the valve seat 16 varies in different makes and models of sprinkler heads and the preferred form of our invention contemplates the provision of a shut-off tool that may be adjusted to meet the requirements for use with the particular sprinkler heads they are to service.

The particular form of guard 9 in Fig. 6 is merely shown by way of example to emphasize the point that the primary unit 10 may be used to stop the flow of liquid without removing the guard. Briefly the guard comprises an attaching spider 25 secured to the body 13 of the sprinkler head adjacent the shoulder 19, and a wire basket-like portion 26 carried by the spider, the vertical wires 27 of portion 26 being spaced apart a distance sufficient to accommodate portions of the unit 10 inserted therebetween.

Referring now to the primary unit 10, it preferably comprises a lever 28 provided with a handle 29 at one end and a head portion 30 at the other end. In practice the major portion of this unit may be inexpensively made from a flat bar of metal, bent intermediate its ends to form the lever portion and the handle portion, and having its end remote from the latter, bent at an acute angle and tapered to provide a tongue 31 which assists in the placing of the tool and forms a part of the head portion 30.

The head portion also preferably includes a stem 32 adapted to enter the port 15 and a valve 33 for engaging the valve seat 16.

In practice we prefer to provide the tongue 31 with a curved guide surface 34 for sliding engagement with the abutment 23, this curved face being tangential to a flat surface 35 located at one side of the lever head, opposite to the side thereof from which the stem 32 extends. The stem 32 is preferably threaded, as at 36, throughout the major portion of its length; and it has its one end received in a screw threaded bore 37 and a countersink 38 formed in the lever 28, the end of the stem being flattened as at 39 to fill the countersink and prevent rotation of the stem with respect to the lever; and it also has a cylindrical stud-like portion 40 at its free end of a diameter at least as great as that of the threaded portion 36. The stud-like portion 40 preferably has its free end rounded, as at 41, to guard against injury to the valve seat 16 and to facilitate placing of the preferred form of valve 33 on the stem 32 as hereinafter described. This stem 32 is preferably disposed with its axis normal to the flat surface 35 and adjacent to the juncture between the surfaces 34 and 35. Thus the lever 28 may be canted to guide the stud-like portion 40 of stem 32 into the port 15, with the curved surface 34 sliding with respect to abutment 23.

The valve 33 is preferably adjustable along the stem 32 by means 42 which, in the example shown, comprises an abutment washer 43 a feed nut 44 engaging the washer and a lock nut 45 engaging the nut 44. The valve 33 is preferably made of two perforated disc-like members 46 and 47 of compressible material, such as rubber, the member 46 engaging the washer 43 and the member 47 engaging the member 46. The bore or perforation 48 of each of said members is preferably made with a diameter less than the diameter of stud-like portion 40 so that the members 46 and 47 must be forced upon the latter and engage it with intimate contact. The rounded terminal 41 of the stud-like portion 40 facilitates placing of the valve members. By feeding the nuts 44 and 45 along the thread 36 the position of rest of the valve may be adjusted for firmly sealing the port 15 when the unit 10 is used to temporarily shut off the flow of liquid from the sprinkler head, as is obvious from an inspection of Figs. 4, 5 and 6.

As to the secondary unit 11 it is not engaged with the sprinkler head if the latter is not broken, but only set off due to melting of the fusible link of the usual sprinkler head valve, and it is desired to use the unit 10 as a shut-off device. However unit 11, being connected to unit 10 by flexible unit 42, the former may hang from the handle portion 29, acting as a signal and assisting in holding the lever 28 in a shut-off position.

The unit 11 preferably comprises a yoke 50 consisting of a base portion 51 and parallel arms 52 and 53; a handle 54 secured to the base portion 51 as by rivets or screws 55; and, an adjustable abutment device 56 carried by arm 52. The arm 53 is forked to provide a recess 57 receiving the body portion of the sprinkler head, and tines 58 which engage upon the shoulder 19 when the unit 11 is in place as shown in Fig. 7, in association with a broken sprinkler head. The arm 52 is preferably provided with a screw threaded bore 59 receiving the screw threaded shank 60, of a screw 61, the head 62 of which acts like the abutment 23 of an unbroken sprinkler head for cooperation with unit 11, as shown in Fig. 7. In order that the screw 61 may be effectively held in its adjusted position, according to the characteristics of the sprinkler head it is to service, we provide nuts 63 and 64 on shank 60, the nut 63 engaging one face and the nut 64, the other face of the arm 52.

The operation and advantages of this shut-off tool may well be understood from the foregoing detailed description of the preferred embodiment of our invention, however, it is important to note that it contains no readily separable parts; may be readily adjusted to meet the condition prevailing or met with in connection with the particular sprinkler heads it is to service; and that the units may be quickly and conveniently manipulated to shut off liquid flow from the sprinkler head and retain it closed until the time arrives to recondition the head for further automatic use.

The head of lever 28 is in reality a strut-like head portion adapted to be interposed between the valve seat 16 and the abutment 23 with the valve 33 for engagement with seat 16 bodily adjustable with respect to the terminal end or flat surface 35 whereby the tool may be adjusted to the various spacings of valve seats and abutments of different fire extinguishing sprinkler heads and it is not necessary to produce various sizes of tools to meet the range of sizes of sprinkler

heads produced by various manufacturers and found on the market.

We claim:

1. A device for stopping the flow of liquid from a fire extinguishing sprinkler head of the character having an outlet port, a valve seat surrounding said port and a shoulder exteriorly of the port and spaced from the valve seat, said device comprising means detachably engaging said shoulder, providing an abutment axially aligned with said port and spaced from said valve seat, and a lever provided with a strut-like head portion adapted to be interposed between said valve seat and abutment, said strut-like head portion including a valve for engaging said seat and a terminal end for engaging said abutment.

2. A device for stopping the flow of liquid from a fire extinguishing sprinkler head of the character having an outlet port, a valve seat surrounding said port and a shoulder exteriorly of the port and spaced from the valve seat, said device comprising means detachably engaging said shoulder, providing an abutment axially aligned with said

port and adjustable toward and from said valve seat, and a lever provided with a strut-like head portion adapted to be interposed between said valve seat and abutment, said strut-like head portion including a valve for engaging said seat and a terminal end for engaging said abutment.
